PAUL LENART, OF COLOGNE, GERMANY.

MIXING APPARATUS.

Application filed December 17, 1927, Serial No. 240,732, and in Germany December 28, 1926.

The invention relates to mixing apparatus comprising two containers arranged one within another and with which the materials to be mixed leaving the inner container at the bottom are supplied again to this container in a cycle by means of a centrifugal disk on the way through the annular space existing between the inner and outer container. Mixing apparatus of this type have turned out very well in practice in all cases where the most intimate possible distribution of powdered or grained substances in liquids is to be obtained, as with these apparatus only a fraction of the time required with the hitherto known mixing apparatus, and a lower consumption of power is required, to obtain a completely homogeneous mixture.

Now my invention has for its object to so improve mixing apparatus of this type as to enable a further acceleration of the mixing procedure and a raise of the mixing intensity, and to afford at the same time the possibility of treating with the same good effect larger or smaller quantities in one and the same mixing apparatus. These objects are obtained primarily by the fact, that apertures are provided in the wall of the inner container, the passage area of which apertures is adjustable, these apertures permitting a suitable portion of the materials to be mixed to directly pass from the annular space into the inner container. This arrangement affords the possibility of using the apparatus even when only its bottom is covered with the materials, as in this case the materials need to rise only to the apertures provided in the inner container, to describe the cycle, which would be impossible when, as hitherto, the liquid would have to rise to the upper edge of the inner container. But even with the mixing apparatus being normally filled, the said apertures in the wall of the inner container afford an important advantage, as they make a greater or less proportion of the liquid enter the inner container laterally, according to the more or less free passage area of the apertures. The divisional liquid currents thus obtained, which flow into the inner container in different directions, cause an intense whirling and thereby considerably improve the mixing effect. When the apertures are further designed as slots and guide plates are arranged in con-

nexion with them of a configuration of 55 turbine guide blades, the material circulating in the annular space enters the inner container through the slots in inverse direction, whereby the mixing effect is still further improved. The guide plates can be made 60 adjustable, to regulate both the passage area and the direction of the currents.

In order that my invention may be more easily understood, some preferred embodiments of the same are illustrated in the 65 drawing which accompanies and forms part of this specification. In this drawing:

Figure 1 is a vertical section through my improved mixing apparatus,

Figure 2 is a section on line II-II of 70 Figure 1,

Figures 3 and 4 are corresponding sections through somewhat modified apparatus, and

Figures 5 and 6 show two constructions of the centrifugalizing disk. 75

Referring to these Figures, 9 denotes the outer container or shell of the apparatus and 10 the inner container which has a bottom aperture 11 closed by a sieve plate 12. To avoid dead spaces, the wall of the inner container 10 subsides with a suitable curvature into the bottom. Underneath the sieve bottom 11 is arranged a centrifugalizing disk 13 which is rotated in any suitable manner, e. g. by the drive 14. This disk may be designed like a fan, as illustrated in Figure 5, or as a real disk, as shown in Figure 6, which disk has blades 15 and 16 on both sides, and openings 17.

Openings, preferably slots 18 are provided in the wall of the inner container 10, which slots either have no regulating means, or are equipped, as shown in Figure 2, with turbine blade-like guide plates 19, by which the liquid circulating in the annular space is 90 led through the slots 18 into the inner container in reversed direction. As illustrated in Figure 4, these guide plates can be made adjustable, by mounting them rockingly on pins 20 and connecting them to a common 95 adjusting ring 22 e. g. by means of links 21. A clamping means 23 may be provided for ring 22, to adjust it from outside, so that the possibility is given to regulate both the passage area of the slots 18 and the guide angle 100 of the plates 19.

As can be seen from Figure 3 the guide plates may be dispensed with and slides 24

may be arranged to vary their passage area. The slides 24 may be adjusted either individually or in common.

The described mixing apparatus operates as follows:

The material supplied to the apparatus and consisting of a liquid and pulverous or grained substances, fills the apparatus about up to the level denoted by 26. Now when the 10 centrifugalizing disk 13 is set in rotation, the liquid with the solid substances is delivered from the inner container into the annular space existing between the inner and outer container in the direction of the arrows, 15 Figure 1, and rise in this annular space until it returns to the inner container over the upper edge thereof, and describes thus a cycle.

At the same time, according to the adjusted 20 passage area of the slots 18, a portion of the material enters the inner container directly through these slots. A manifold subdivision of the material partaking of the cycle is thus obtained, and a subsequent 25 reunion thereof in the inner container 10, whereby the mixing effect is considerably improved. This effect is still further increased by arranging the guide plates shown in Figures 2 and 4 that cause the material 30 entering the container 10 through the slots 18 to undergo a deflection in the direction of the arrows, Figures 2 and 4.

When the apparatus is filled only partially, e. g. about up to the level 27 only, then 35 it is impossible in itself, for the liquid to return to the inner container over the upper edge thereof, because the liquid quantity is too small to fill the annular space up to said upper edge. In this case the whole material 40 enters the inner container through the slots 18. These slots thus enable the cycle, which forms the essential feature of the operation, to be attained also with an incomplete filling 45 of the apparatus, so that the range of use of one and the same apparatus is notably enlarged. When the liquid contains 50 foreign substances, they can be removed by withdrawing the sieve bottom 12, by lifting it. This can be executed even during the operation of the apparatus.

What I claim, is:—

1. A mixing apparatus comprising two containers arranged one within the other and with the inner one spaced from the other at sides and bottom to form an annular space 55 between them, said inner container having openings in its bottom, and means for pumping the material to be mixed downward through said bottom openings and upward in said annular space, said inner container being provided with openings in its side walls adapted to permit the material to flow back into said inner container from said annular space.

65 2. A mixing apparatus in accordance with

claim 1 in which said pumping means comprises a centrifugal arranged between the bottoms of the two containers.

3. A mixing apparatus comprising two containers arranged one within the other 70 and with the inner one spaced from the other at sides and bottom to form an annular space between them, said inner container having openings in its bottom, and means for pumping the material to be mixed downward 75 through said bottom openings and upward in said annular space, said inner container being provided with vertical slots in its side walls adapted to permit the material to flow back into said inner container from 80 said annular space.

4. A mixing apparatus comprising two containers arranged one within the other and with the inner one spaced from the other at sides and bottom to form an annular space 85 between them, said inner container having openings in its bottom, means for pumping the material to be mixed downward through said bottom openings and upward in said annular space, said inner container being provided with openings in its side walls 90 adapted to permit the material to flow back into said inner container from said annular space, and means for varying the sectional area of said side openings.

5. A mixing apparatus comprising two containers arranged one within the other and with the inner one spaced from the other at sides and bottom to form an annular space between them, said inner container having openings in its bottom, means for pumping the material to be mixed downward through said bottom openings and upward in said annular space, said inner container being provided with openings in its side walls 100 adapted to permit the material to flow back into said inner container from said annular space, and guide plates mounted near said side openings adapted to control the direction of flow of material passing through 105 the same.

6. A mixing apparatus comprising two containers arranged one within the other and with the inner one spaced from the other at sides and bottom to form an annular space 115 between them, said inner container having openings in its bottom, means for pumping the material to be mixed downward through said bottom openings and upward in said annular space, said inner container being provided with openings in its side walls 120 adapted to permit the material to flow back into said inner container from said annular space, means for varying the sectional area of said side openings, and guide plates at 125 said side openings adapted to control the direction of flow of material passing through the same.

7. A mixing apparatus comprising two containers arranged one within the other and 130

- with the inner one spaced from the other at sides and bottom to form an annular space between them, said inner container having openings in its bottom, means for pumping the material to be mixed downward through said bottom openings and upward in said annular space, said inner container being provided with openings in its side walls adapted to permit the material to flow back into said inner container from said annular space, and guide plates at said side openings for varying the sectional area thereof and for controlling the direction of flow of material passing therethrough.
8. A mixing apparatus comprising two containers arranged one within the other and with the inner one spaced from the other at sides and bottom to form an annular space between them, said inner container having openings in its bottom; means for pumping the material to be mixed downward through said bottom openings and upward in said annular space, said inner container being provided with openings in its side walls adapted to permit the material to flow back into said inner container from said annular space, guide plates mounted near said side openings and adapted to control the direction of flow of material passing through the same, and means for adjusting said guide plates.
9. A mixing apparatus comprising two containers arranged one within the other and with the inner one spaced from the other at sides and bottom to form an annular space between them, said inner container having openings in its bottom, and means for pumping the material to be mixed downward through said bottom openings and up-
- ward in said annular space, said inner container being provided with openings in its side walls adapted to permit the material to flow back into said inner container from said annular space, the side walls of said inner container curving gradually into the bottom walls thereof.
10. A mixing apparatus comprising two containers arranged one within the other and with the inner one spaced from the other at sides and bottom to form an annular space between them, said inner container having an opening in its bottom, an easily detachable sieve fitted into said opening, means for pumping material to be mixed downward through said sieve and upward in said annular space, and openings in the side walls of said inner container adapted to permit the material to flow back into said inner container from said annular space.
11. A mixing apparatus in accordance with claim 1 in which said pumping means consists of a disk having upper and lower centrifugal ribs and openings cooperating with those in the bottom of said inner container, said disk being arranged between the bottoms of said two containers.
12. A mixing apparatus in accordance with claim 8 in which said adjusting means comprises a ring mounted concentrically with said containers, a link connecting each of said guide plates with said ring, and means accessible from the outside for adjusting said ring circumferentially.

In testimony whereof the foregoing specification is signed.

PAUL LENART.
